Primary Examiner — Abraham Bahta(74) *Attorney, Agent, or Firm* — Taylor English Duma LLP(57) **CLAIM**

We claim the ornamental design for a lawn refuse bag, as shown and described.

DESCRIPTION

FIG. 1 is a top perspective view of an aspect of the lawn refuse bag in an assembled configuration.

FIG. 2 is a right-side elevation view thereof.

FIG. 3 is a left-side elevation view thereof.

FIG. 4 is a front elevation view thereof.

FIG. 5 is a rear elevation view thereof.

FIG. 6 is a top plan view thereof.

FIG. 7 is a bottom plan view thereof; and,

FIG. 8 is a top plan view of the lawn refuse bag of FIG. 1 in a blank configuration.

The features shown in dashed lines in FIG. 8 represent bend lines.
